MANICURE SET

Georgette Mirmann, Joinville le Pont, France

Application December 30, 1931, Serial No. 583,800
In France February 2, 1931

14 Claims. (Cl. 132—73)

The present invention relates to manicuring sets, and has for its object a manicure set foldable and containing all utensils necessary for the toilet of hands.

5 It is a further object of the invention to provide a manicuring set which may be folded together in a compact manner and when opened serves as a buffer.

The buffer comprises two shells connected to 10 each other by an appropriate articulation and containing on one of their sides a polishing surface, which buffer is foldable for shipment, and when unfolded the polishing surfaces of both shells are in one plane.

15 It is also an object of the invention to secure the polishing skin on the two shells in an efficient manner.

Another object of the invention consists in that the side opposite the polishing surface of one of 20 these shells forms a cover connected to said shell by an appropriate hinge, there being compartments provided in the interior of this shell for containing pastes, powder and so on.

It is also an object of the invention to provide a 25 cap hingedly connected to the inner end of one of the shells, which cap constitutes a handle and also serves as a cover for the open inner end of the other shell.

It is also an object of the invention to provide 30 certain details of construction and arrangement tending to enhance the utility and desirability of a device of the character described.

With these and other equally important objects in view which will become apparent from a 35 perusal of the invention, the latter comprises the means described in the following specification, particularly pointed out in the claims forming a part thereof, and illustrated in the accompanying drawing, in which:

40 Fig. 1 is a perspective view of a manicuring set unfolded for use as a buffer.

Fig. 2 is a perspective view from the bottom side of the device, disclosing the means for securing the polishing skin.

45 Fig. 3 is a perspective view of the device in folded position with the cap tilted to afford access to the interior of one shell.

Fig. 4 is a perspective view of the folded device, with the cover of one shell opened disclosing 50 an inner compartment in the shell and a hinged cover therefor.

Fig. 5 is a fragmentary perspective view of a shell of slightly modified construction; and

55 Fig. 6 is a fragmentary side view of the shell

with a cuticle stick held thereby in operative position.

The manicure case, according to the invention, comprises two shells 1 and 2, (Figs. 1 and 2) articulated at 3 and 4 to a central rod 5. On the 60 same articulations are pivotally secured two plates 6 and 7, to which a polishing skin 8 is secured.

In order to facilitate securing of this skin, the plates 6 and 7 are provided with lateral teeth 9 65 penetrating into the skin and preventing the same from detaching itself from these plates. A sponge of india-rubber or other soft material serves as stuffing means for the polishing skin 8 to maintain the same under tension. 70

The plate 6 rests on the bottom 1a with downwardly projecting prongs.

The other plate 7 rests on an intermediate plate 11 fixed in the shell 2.

The plate 6 is kept in the shell 1 by the friction of the tongue 10a against the rim of this shell. 75

The plate 7 is held in place by a small pin 12 penetrating into an aperture 13 provided in this plate. 80

The two shells can be folded together as shown in Fig. 4, and can be closed in this position by means of a latch 14 (Fig. 1) articulated to the shell 2 and engaging over a pin 15 provided on the shell 1, the two shells being kept parallel to 85 each other by the engagement of the pin 12 with the plate 6.

On opening the case, the same may be used as a buffer (Fig. 1).

A cap 16 is articulated to the shell 2, and is 90 provided with a cover 17 and with several compartments 18 containing products necessary for the care of nails or of the skin. This cap serves as a handle in manipulating the unfolded case as a buffer. 95

To one side of the cap 16 is articulated, (Fig. 2) as at 19, a plate 20 provided with a pin 21. This pin can engage two holes 22 and 23 provided in the wall of the shell 1, and serves to maintain the case rigid in open position when used as a buffer, the pin engaging for this purpose the hole 22. When the shells are superposed, the pin 21 enters the opening 23 to secure the shells in compact arrangement. 100

The cap 16 is articulated at 24 to the shell 2 (Fig. 3), in such manner that it uncovers the space provided between the bottom 1a of the shell 1, and the plate 6. This space is utilized for lodging therein the different utensils such as the 105

110

nail file 25, the cuticle stick 26, the scissors 27, and so on.

The shell 2 is provided with a cover 28 pivotally secured at 29 and uncovering the space 5 formed by the lateral walls of the shell and by the intermediate plate 11. In this space is provided a small compartment 30 closed by a cover 31.

These spaces are destined to receive cosmetics 10 such as the lip stick, the powder and puff, and so on.

The case can be constructed in such manner as to serve as a handle for the manicure utensils. For this purpose, the plate 7 is a little shorter 15 and the intermediate plate 11 carries two pins 32 engaging holes provided in the tools, such as the nail file 25, in the cuticle stick 26 and so on.

It is obvious that the manicuring case, as described, permits manifold modifications, both 20 with regard to the general arrangement and to the details.

It permits any outer decoration, of another number and arrangement of the different compartments, and so on.

25. I claim:

1. A manicuring set, comprising a pair of shells pivotally secured together and adapted to be folded on one another and constituting a buffer in open position.

30. 2. A manicuring set, comprising a pair of shells pivotally secured together and adapted to be folded on one another, and a skin covering the bottom of each shell to constitute a buffer in the open position of said shells.

35. 3. A manicuring set, comprising a pair of shells pivotally secured together, said shells being adapted to be folded on one another and having their bottoms in alignment when opened.

40. 4. A manicuring set, comprising a pair of hollow shells each containing compartments for the reception of utensils, said shells being adapted to be folded on one another, and having their bottoms in alignment when opened.

45. 5. A manicuring set, comprising a pair of shells pivotally secured together, and adapted to be folded on one another, a skin covering the bottom of each shell and constituting a buffer surface in the open position of said shells, and means for maintaining said skin in taut condition 50 on said shells.

55. 6. A manicuring set, comprising a pair of shells, a double hinge connecting said shells, said shells being adapted to be folded on one another and complementing each other to form a buffer in opened position.

7. A manicuring set, comprising a pair of shells, a double hinge connecting said shells, said shells being adapted to be folded on one another and

complementing each other to form a buffer in opened position, and means for locking said shells in folded and in opened position, respectively.

8. A manicuring set, comprising a pair of shells pivotally secured together, said shells being adapted to be folded on one another and complementing each other to form a buffer in opened position, and a cap pivotally secured at the inner end of one of said shells and constituting a handle. 80

9. A manicuring set, comprising a pair of shells pivotally secured together, said shells being adapted to be folded on one another and complementing each other to form a buffer in opened position, and a cap pivotally secured at the inner end of one of said shells and constituting a handle, said cap having means to lock said shells in open and folded position, respectively. 85

10. A manicuring set, comprising a pair of shells pivotally secured together, said shells being adapted to be folded on one another and complementing each other to form a buffer in opened position, and a cap containing a compartment pivotally secured at the inner end of one of said shells and constituting a handle. 90

11. A manicuring set, comprising a pair of shells pivotally secured together, said shells being adapted to be folded on one another and complementing each other to form a buffer in opened position, a cap containing a compartment pivotally secured at the inner end of one of said shells 100 and constituting a handle, and a cover closing said cap.

12. A manicuring set, comprising a pair of shells pivotally secured together, said shells being adapted to be folded on one another and complementing each other to form a buffer in opened position, a cap containing a compartment pivotally secured at the inner end of one of said shells 110 and constituting a handle, and a cover closing said cap, said cap having means for locking said shells in open and folded positions, respectively. 115

13. A manicuring set, comprising a pair of shells, a double hinge connecting said shells, said shells being adapted to be folded on one another and complementing each other to form a buffer in opened position, one of said shells being hollow, a cover hingedly secured to said one shell to close the same, a compartment in said shell, and a cover for said compartment hinged to said shell. 120

14. A manicuring set, comprising a pair of hollow shells pivotally secured together, said shells being adapted to be folded on one another and complementing each other to form a buffer in opened position, and a cap pivotally secured to the inner end of one of said shells and constituting a handle, said cap forming cover for the open inner end of said other shell. 125
